UNITED STATES PATENT OFFICE

JOSEPH J. STEINHARTER, OF NEW YORK, N. Y., ASSIGNOR, BY DIRECT AND MESNE ASSIGNMENTS, TO CABLE RADIO TUBE CORPORATION, OF BROOKLYN, NEW YORK, A CORPORATION OF DELAWARE

HANDLING AND SHIPPING APPARATUS

Application filed May 3, 1928. Serial No. 274,692.

This invention relates to shipping containers, and particularly to containers for housing articles that are extremely fragile, such as neon lamps.

5 The invention aims to provide a structure in which the lamp is mounted on a resilient support which is carried in such a way that the lamp is spaced a safe distance from the sides of the container.

10 A further object resides in the provision of a frame chassis member on which the lamp is resiliently secured, and which can be handled in packing, unpacking, and preparing the lamp for its permanent mounting without 15 actually touching the lamp itself.

While preferred forms of the invention have been set forth for purposes of illustration, it should be understood that various changes and modifications may be made in 20 the structure without departing from the spirit and scope of the invention as herein-after set forth and claimed.

In the drawings:

Fig. 1 is a section on line 1—1 of Fig. 2.

25 Fig. 2 is a plan view of a container embodying the invention.

Fig. 3 is a perspective view of the chassis.

Fig. 4 is a perspective with parts broken away of a container adapted to hold a plurality of tubes.

Referring to the drawings more particularly, the reference numeral 10 indicates the frame, or chassis, to which the lamp is attached. This frame may be formed in any 35 suitable manner to obtain the necessary strength and lightness, as by joining together pieces of wood. The supports 11, which cross the frame and carry the lamp, are composed of some elastic material, such as rubber. A plurality of these supports cross the 40 chassis in each direction, and they are anchored against slipping along the sides of the chassis in any convenient manner, as by engagement with the notches 13. A plurality 45 of these notches are formed in each side of the frame so that the spacing of the supports 11 may be altered, if necessary, to accommodate a lamp of any particular shape.

The neon lamp is attached to the chassis by 50 laying it against the supports 11 and suit-

ably securing it to the supports, for example by tying with cords 14. For lamps shaped into certain letters it may be advisable to change the spacing of certain of the supports 11 in order to provide sufficient contact for the lamp, but it will be clear that the plurality of adjustable supports 11 provides adequate attachment for a lamp of any shape.

The container proper is a box 15 formed of corrugated paper or any other material, formed of such a size that the chassis 10 fits snugly therein. When a single lamp is packed in each box the arrangement shown in Figs. 1 and 2 is used.

In this case the chassis is held away from the bottom of the box by spacers 16, which may be separate pieces of any light material secured to opposite sides of the box or they may be parts of a continuous spacer extending around the box. After the spacers 16 have been positioned the chassis carrying the lamp is placed thereon and the top spacers 17 are then secured in the box. The spacers 17 may be of similar construction to spacers 16. The top of the box is closed by flaps or lids 75 of any desired construction.

Inspection of Figs. 1 and 2 will show that the construction disclosed resiliently supports the lamp in such a position that it is spaced from all sides of the container a sufficient distance to prevent its contacting with the container under any of the shocks incident to transportation.

Figure 4 shows how a plurality of the tubes may be packed in a single large container. For this purpose the spacers 16 are put against one end of the box 18, a chassis carrying a tube is then placed against spacer 16 in a vertical position, and spacers 17 are placed on the opposite side of the chassis. A second loaded chassis is next moved into position followed by a second set of spacers 17. In a similar manner any number of the lamps may be packed in a container of suitable size and construction.

When the tubes are being unpacked by the consignee, it is unnecessary for him to touch the tube itself, since the chassis provides a convenient means for handling. Even during the preliminary stages of installation the

tube may be allowed to remain on the chassis, thereby preventing direct handling of the tube until everything is ready for the permanent installation.

5 A person skilled in the art will readily understand the advantages of the present invention in eliminating the usual high percentage of breakage in the shipping and handling of delicate articles such as neon 10 lamps.

I claim:

1. An article supporting device consisting of a substantially rigid frame, and intersecting endless elastic bands embracing 15 said frame said bands being of rubber thin enough and having sufficient stretch to yield readily to the weight of an article secured thereto.

2. An article supporting device consisting 20 of a substantially rigid frame having oppositely disposed adjustment notches, and endless elastic bands embracing the frame and engaging in said notches said bands being of rubber thin enough and having sufficient stretch to yield readily to the weight of an article secured thereto.

3. An article supporting device consisting 25 of a substantially rigid frame having parallel sides provided with series of adjustment notches, and endless elastic bands embracing said frame and engaging in selected notches said bands being of rubber thin enough and having sufficient stretch to yield readily to the weight of an article secured thereto.

35 4. An article supporting device consisting of a rectangular frame having peripheral adjustment notches arranged in opposed series on the sides of the frame, endless elastic bands encircling the frame in one direction 40 and engaging selected notches of two of the frame sides, and other endless elastic bands encircling the frame substantially at right angles to the first bands and engaging selected notches in the remaining sides said bands 45 being of rubber thin enough and having sufficient stretch to yield readily to the weight of an article secured thereto.

In testimony whereof I affix my signature.

JOSEPH J. STEINHARTER.
